(57) **CLAIM**

The ornamental design for a pop-up shelter with solar panels and USB charging station, as shown and described.

DESCRIPTION

FIG. 1 is a top, front and left side perspective view of a pop-up shelter with solar panels and USB charging station showing our new design;

FIG. 2 is a top plan view of the pop-up shelter with solar panels and USB charging station;

FIG. 3 is a left side elevation view of the pop-up shelter with solar panels and USB charging station, with the right side elevation view being a mirror image of FIG. 3;

FIG. 4 is a front view of the pop-up shelter with solar panels and USB charging station, with the rear view being a mirror image of FIG. 4; and,

FIG. 5 is a bottom plan view of the pop-up shelter with solar panels and USB charging station.
